H. FURSTE

DISPLAY DEVICE

Filed June 1, 1925

Inventor

Henry Furste,

Murray and Gugelton

Attorneys.

UNITED STATES PATENT OFFICE.

HENRY FURSTE, OF CINCINNATI, OHIO, ASSIGNOR TO THE UNITED STATES PRINTING & LITHOGRAPH COMPANY, OF CINCINNATI, OHIO, A CORPORATION OF OHIO.

DISPLAY DEVICE.

Application filed June 1, 1925. Serial No. 33,964.

To all whom it may concern:

Be it known that I, HENRY FURSTE, a citizen of the United States of America, and a resident of Cincinnati, in the county of 5 Hamilton and State of Ohio, have invented new and useful Improvements in a Display Device, of which the following is a specification.

An object of my invention is to provide a 10 display device which is adapted, when in an operative position, to present to the observer the appearance of a container.

Another object is to provide a display 15 device of this kind which may assume the form of a single flat sheet so that it may be conveniently stored and shipped.

Another object is to provide a device of 20 this kind which is novel in appearance and economical of manufacture.

Another object is to provide a device of 25 this kind in which a maximum of space is utilized for display or advertising purposes and in which a negligible amount of stock is wasted.

These and other objects are attained by 30 the means described herein and disclosed in the accompanying drawings, in which:

Fig. 1 is a perspective view of the device 35 of my invention, parts being broken away.

Fig. 2 is a plan view of the device in a 40 flattened position which it may assume in order to be economically packed.

As shown in Fig. 2, the device of my invention comprises a single sheet 5 of suitable 45 foldable material such as card stock which is provided with a main display panel 6 suitably printed or decorated and a small auxiliary display panel 7 disposed interiorly of the remaining portion of the sheet 5.

This remaining portion of sheet 5 constitutes 50 a foldable back panel 26. As will be observed in Fig. 2, the printing or decoration of panel 7 is inverted with relation to that of panel 6. The panels 6 and 7 are

decorated at a single operation after which 55 the sheet 5 is slotted, scored and perforated as hereinafter described. These latter operations may also be performed at one time by using a combined scoring and cutting die in a manner well known to those conversant 60 with the art. The printing or decorating is placed on only one face of the sheet 5 so that the card stock need have only a single

finished face and the device may therefore be made of comparatively inexpensive stock. 55 The only waste occurs in cutting away two corner pieces of the sheet 5 in order to form tongues 8 and notches 9 adjacent the opposite ends of the free end 27 of back panel 26. The slots 10 are cut in spaced relation adjacent the top edge of sheet 5 and the perforations 11 may be provided adjacent scored lines 12, if desired. The panel 7 has its side edges 13 and top edge 14 cut free of the remainder of the sheet 5 and is provided with a pair of integral ears 15 also cut free of the sheet 5. The edges 16 of ears 15 are cut for a distance into the body of the panel 7 and terminate at points 17. The slits 18 extend from scored line 19 to 70 the edges 16 of ears 15 so that the panel 7 is hingedly connected to sheet 5 and may be swung about its hinged connection and folded against the body of sheet 5 adjacent the scored line 19. If desired, the points 17 75 may have a scored line 21 connecting them. In this way a hinge panel 22 is formed. The panel 7 is then bent in the opposite direction along scored line 21 until panel 7 assumes a position substantially at right 80 angles with the back panel 26 and the hinge panel 22 will lie in abutment with the face of back panel 26. The ears 15 will then be passed over the top edge 20 of the sheet and when the panel 7 is again bent about scored 85 line 21, the ears 15 will be disposed upon the rear face of panel 26. The ends of ears 15 may then be passed through the slots 10 so that said ears and the hinge panel 22 are disposed upon the rear and front faces 90 respectively of the panel 26. A pair of substantially U-shaped slits 23 are cut intermediate the side edge 24 of the sheet 5 and the scored line 12 adjacent thereto so that these slits are located in the narrow foldable strip 25 and are spaced so as to receive 95 therein the tongues 8. The notches 9 afford clearance so that the tongues 8 may be readily inserted into the U-shaped slits 23. When the tongues 8 are inserted in the 100 U-shaped slits 23, the main display panel 6 is bulged outwardly because the back panel 26 is relatively narrower than the main panel 6. In the form shown, the panel 6 being free of scoring, assumes a substantially semicylindrical form and the back 105

panel 26 forms a closure therefor so that a hollow body open at its top and bottom is formed.

As will be noted from Fig. 2, the decorated panel 6 carries a foldable strip 25 at its right hand side and the foldable back panel 26 at its left hand side. The panel 26 comprises that portion of the sheet 5 from which the panel 7 is cut. By creasing the sheet 5 along the scored lines 12, the panel 6 may be bent to assume an arcuate form as previously explained, and the tongues 8 may then be inserted into the U-shaped slits 23 for retaining the panel 6 in an arcuate form 15 with the panels 25 and 26 locked upon one another. While the panel 6 is disclosed in Fig. 1 as assuming an arcuate or semicylindrical form, it will be readily apparent that it may take the form of a polygonal body by 20 providing one or more scored lines extending in parallelism to the lines 12 and disposed intermediate the scored lines 12. The major panel 6, must in all events, be of a greater length between the scored lines 12 25 than the panel 26 between scored lines 12 and its outer edge 27. The panel 26 and foldable strip 25 are normally hidden by panel 6 when said panel is held in its arcuate or semicylindrical shape and therefore 30 the surface of the panel 26 would be valueless for advertising or display purposes. By cutting the panel 7 free of the panel 26 and by folding said panel upwardly, it will be apparent, as shown in Fig. 1, that a large 35 portion of the panel 26 may be utilized for a supplemental display panel such as 7. By placing the decorative matter on the panels 6 and 7, in an inverted position one to the other, the panel 7, when turned upwardly 40 as shown in Fig. 1, will display its printing or decorative matter in an upright position above the top edge 20 of the sheet so that the entire device presents the appearance of a hollow container with an additional display panel projecting above it. The perforations 11 may have a piece of 45 cord or the like passed through them and the entire device may be suspended therefrom against a vertical wall.

50 What I claim is:

1. In a device of the class described the combination with a flexible display panel, a slotted back panel hingedly mounted along one edge of the display panel, a slotted strip 55 hingedly mounted along the opposite edge of the display panel, tongues carried by the free edge of the back panel and insertible in the slits in the strip whereby the flexible display panel and back panel together may form a hollow body open at its top and bottom, an auxiliary display panel cut from the body of the back panel and hingedly connected thereto, said auxiliary panel being foldable upon said back panel to assume a 60 position projecting beyond the body lines of 65

the said back panel, and means comprising ears insertible in the slots in the back panel for retaining the auxiliary panel in the last named position.

2. In a display device, a single sheet of 70 flexible material comprising a bendable display panel, a slotted back panel hingedly mounted at one side of the display panel, a slotted strip hingedly mounted at the opposite side of the display panel, means for locking the free end of the back panel upon the slotted strip whereby the display panel and back panel may form a hollow body open at its top and bottom, an auxiliary display panel cut from the body of the back 75 panel and hingedly connected thereto, integral ears carried by the auxiliary panel, the ears of said panel being adapted to be passed over the top edge of the back panel by moving said panel about its hinge mounting, the ears being insertible in the slots in the back panel for retaining the auxiliary panel in alignment with and extending above the back panel.

3. In a device of the class described the combination with a bendable display panel, of a back panel hingedly mounted along one edge of the display panel, a slotted foldable strip hingedly mounted along the opposite edge of the display panel, ears on 90 the free edge of the back panel and insertible in the slits in the foldable strips whereby the display panel and back panel together form a hollow body open at its top and bottom, an auxiliary panel, a hinge member connected to the back panel adjacent the top edge thereof, the auxiliary panel having a hinge connection upon the hinged panel, integral ears on the auxiliary panel 95 adapted to be passed over the top edge of the back panel upon movement of the hinge member and auxiliary panel whereby the hinge member and the ears may be disposed on opposite faces of the back panel with the auxiliary panel extending beyond and in alignment with said back panel, the ears being insertible in the slots in the back panel 100 for retaining the auxiliary panel in the last mentioned position.

4. In a device of the class described the combination with a bendable display panel, a back panel hingedly mounted along one edge of the display panel, means for connecting the opposite edge of the display panel and the free edge of the back panel and an auxiliary panel cut from the body of the back panel and foldable upon itself whereby the auxiliary panel is disposed above and in alignment with the back panel, 115 and means comprising ears for locking the auxiliary panel in the last named position.

5. In a device of the class described the combination of a single sheet of flexible material adapted to be bent to form a hollow body, open at its top and bottom, a 120

panel cut from the body of the sheet and adapted to be folded upwardly to project above the top of the hollow body, and means for securing said panel in the last mentioned position.

6. In a device of the class described the combination of a sheet of material having slits at a side edge thereof and slots adjacent its top edge, tongues carried by a second side edge for insertion in the slits whereby the sheet may have its side edges secured one

upon the other for forming a hollow body, and a panel having ears cut from the body of the sheet and foldable thereon so that said panel may project above the top of the hollow body and the ears may enter the slots.

In testimony whereof I have hereunto subscribed my name this 29th day of May, 1925.

HENRY FURSTE.
